(57) **CLAIM**

The ornamental design for a enclosure, as shown and described.

DESCRIPTION

FIG. 1 is a perspective view of the enclosure showing my new design;

FIG. 2 is a front elevational view of the enclosure of FIG. 1;

FIG. 3 is a rear elevational view of the enclosure of FIG. 1;

FIG. 4 is a side elevational view of the enclosure of FIG. 1,

the opposite side being a mirror image thereof;

FIG. 5 is a top plan view of the enclosure of FIG. 1; and,

FIG. 6 is a bottom plan view of the enclosure of FIG. 1.

The broken lines showing additional detail are for illustrative purposes only and form no part of the claimed design.
